US00D710985S

(12) **United States Design Patent**
Gassman et al.

(10) **Patent No.:** US D710,985 S
(45) **Date of Patent:** ** Aug. 12, 2014

(54) **ROOF VENT**

- (71) Applicant: **Owens Corning Intellectual Capital, LLC**, Toledo, OH (US)
- (72) Inventors: **Paul E. Gassman**, Newark, OH (US); **Christopher C. Freidner**, Granville, OH (US)
- (73) Assignee: **Owens Corning Intellectual Capital, LLC**, Toledo, OH (US)

(**) Term: **14 Years**

(21) Appl. No.: **29/434,133**

(22) Filed: **Oct. 10, 2012**

(51) LOC (10) Cl. **23-04**

(52) U.S. Cl.

USPC **D23/373**; D23/386

(58) **Field of Classification Search**

USPC ..... D23/370-385, 411-414, 365, 364, 328, D23/314, 386-394, 259; 415/60, 66, 68, 415/208.1, 213.1, 214.1; 310/257; 361/695; 126/299 D, 299 R; D26/51, 72, 73; D32/15, 16; 416/189; D13/179; 454/358-368; D25/199; 285/13, 43, 285/44; 52/58, 219

(57) **CLAIM**

The ornamental design for a roof vent, as shown and described.

DESCRIPTION

FIG. 1 is a top isometric view of an exemplary embodiment of a roof vent, showing my new design;

FIG. 2 is a bottom isometric view of the roof vent of FIG. 1;

FIG. 3 is a top plan view of the roof vent of FIG. 1;

FIG. 4 is a bottom plan view of the roof vent of FIG. 1;

FIG. 5 is a front view of the roof vent of FIG. 1;

FIG. 6 is a rear view of the roof vent of FIG. 1;

FIG. 7 is a right side view of the roof vent of FIG. 1; and,

FIG. 8 is a left side view of the roof vent of FIG. 1.

The broken lines in the drawings depict environmental subject matter only and form no part of the claimed design.

1 Claim, 5 Drawing Sheets
